UNITED STATES PATENT OFFICE.

ERNEST HUTTON, OF WAYLAND, KENTUCKY.

CROSS-TIE FOR MINE RAILROADS OR TRACK CONSTRUCTIONS.

1,223,171.

Specification of Letters Patent. Patented Apr. 17, 1917.

Application filed November 16, 1916. Serial No. 131,721.

To all whom it may concern:

Be it known that I, ERNEST HUTTON, a citizen of the United States, residing at Wayland, in the county of Floyd and State 5 of Kentucky, have invented new and useful Improvements in Cross-Ties for Mine Railroads or Track Constructions, of which the following is a specification.

This invention relates to ties for mine 10 railroads or track constructions, and the primary object of the same is to provide a tie having a terminal formation adapted to receive and engage rails and hold the latter to gage and also prevent the rail from turning and whereby also the rails may be readily 15 detached when it is desired to shift the track construction from one point to another in mine leads or in other applications of the improved tie. A further object 20 of the invention is to provide a tie for the purposes specified of a cheap and durable character and permitting a rail to be applied thereto with the ball down, especially when driving entries where it is undesirable 25 to cut a rail and under conditions when it is necessary to extend a track a number of feet required to be daily adapted to meet certain contingencies incident to mine track or other analogous constructions.

30 The invention consists in the construction and arrangement of the several parts which will be more fully hereinafter described and claimed.

In the drawing:

35 Figure 1 is a top plan view of a portion of a track construction showing a tie and two rails, and the tie broken away and partially in section, and embodying the features of the invention.

40 Fig. 2 is a transverse vertical section taken in the plane of the line 2—2, Fig. 1.

Fig. 3 is an edge elevation of one extremity of the improved tie showing rails in cross-section therein arranged in normal 45 and ball down positions for extension purposes.

Fig. 4 is a detail perspective view of one extremity of the improved tie.

The numeral 5 designates the body of 50 the tie struck up at opposite extremities in vertical planes, as at 6, and then inwardly and upwardly in inclined planes, as at 7, each extremity being similarly formed; and from the inner terminal of the inwardly inclined portion 7 the end is turned and bent

downwardly, as at 8, and then shaped into a horizontally flat seat member 9 terminating in an upwardly and outwardly directed stop bend 10 which forms a means to engage the inner edge portion of a rail flange. 60 The flat seat member 9 is riveted or otherwise secured to the adjacent portion of the body of the tie, as at 11, and by this means the bent portions 6, 7 and 8 are held in the shape desired and with the body portion of 65 the tie nearest thereto provide an open-ended chamber 12 for a purpose which will be presently explained. The upwardly and inwardly inclined portion 7 and the downwardly bent portion 8 intersect in such manner as to provide an overhanging projection 13 which is shaped or given such contour as to effectively hold a rail when desired with the ball down to prevent such rail from being dislodged or forced upwardly out of place. The body of the tie 5 forming the base of the chamber 12 has a slot 14 formed therein to receive the head 15 of a securing spike 16, said spike being inserted through an opening 17 in the downwardly bent portion 8, the latter forming 70 the inner wall for the chamber 12. The outer vertical wall 6 of the said chamber 12 serves as a bracing wall for a wedge block 18 which is driven longitudinally through the chamber, as shown at the right of Fig. 1, to engage the head 15 of the spike and hold the latter projected inwardly the requisite distance to secure a rail in the seat member 9 when a single rail is disposed in 75 the said seat member, as shown by Figs. 1 and 2. The outer bent portion or wall 6 is formed with an opening 6^a to permit the insertion of an implement to engage the head 15 of the spike 16 to assist in placing 80 or positioning the spike in its clamping application, the spike being driven inwardly to insure a tight fitting thereof relatively to the part of the rail engaged thereby. This opening 85 6^a is not an absolute necessity, as any suitable tool may be inserted longitudinally in the chamber 12 to engage the head of the spike and force the same inwardly. When 90 a rail 19 is applied to the seat member 9 in normal position so that the ball thereof will stand uppermost, the base flange 20 of said rail is held in the seat member 9, the inner edge portion of said flange being engaged 95 under the inner stop bend or limiting means 100 110

10, and when the rail is so disposed an ordinary spike 16 is inserted through the opening 17 and pushed inwardly over the outer side portion of the rail flange, and
5 then a wedge or wedge block 18 is driven into the chamber 12 and the spike is thereby firmly forced inwardly and positively held in engagement with the rail flange, the head 15 of the spike engaging the slot 14 to positively retain the spike in applied position. It will be understood that when the spike 16 is inserted in the chamber the latter will be clear, such spike insertion being effected prior to the introduction of the
10 wedge or wedge block 18.
15 It is often necessary to extend a track in opposite directions a certain number of feet, and to avoid delay in making the necessary extension it would be inexpedient to adopt
20 a cutting operation relatively to the rails to obtain the required number of feet of the extension, and under these conditions a rail is usually inserted ball down in conjunction with a normally positioned rail, the ball down rail, as at 21, being disposed outside of
25 the normally positioned rail, and under these conditions the base flange 22 of such inverted rail serves as a track means and provides for an expeditious track extension. The im-
30 proved tie is constructed to meet this track extension contingency and is provided with an inner projection 13 which engages over the inverted ball 23 of the rail 21, as shown by Fig. 3, the rail 21 in its inverted position
35 being shifted longitudinally through the tie; and the spike 16 has its inner pointed end driven slightly between the ball 23 and the base flange 20 of the normally positioned rail 19 as a support or means for holding
40 the inverted rail in such manner that the flange 22 thereof will be positively maintained in a horizontal position. The spike 16 when used to hold the inverted rail as shown by Fig. 3 has its head projected out-
45 wardly in the chamber 12 and the lower portion of the projection 13 bears on the outer part of the inverted ball 23 of the rail 21. In the arrangement of the spike as shown by Fig. 3 the pressure of the ball 23 of the rail
50 21 forces the spike outwardly, the latter being first inserted in the chamber 12 at an angle through the opening 17, and as the ball 23 is wedged or driven into place the spike 16 recedes or is pushed outwardly, the
55 point only of the spike being held between the rail ball 23 and the flange 20 of the rail 19 with the head 15 of the spike snugly engaging the outer contracted walls of the chamber 12. This extension of the track
60 may be adopted at either end of a track bed organization and the addition of the extension rails in a ball down position may be readily made without disorganizing the general track construction.
65 It is proposed to form the tie either of

channel iron or of flat stock, and in some instances a pipe may be cut and partially flattened and the ends bent into the shape hereinbefore described. If a channel iron be used as shown in the accompanying drawing, the opposite side ribs 24 assume an up-
70 permost position at the opposite bent extremities of the tie, and these ribs in the horizontal seat member 9 serve as the supports for the base flange 20 of the rail, and portions of these ribs which are overturned in the formation of the stop bend or limiting means 10 bear upon the upper surface of the inner side edge portion of the base flange 20.
75

It will be seen that the spike 16 arranged as shown in connection with each rail holding extremity of the tie serves as a clamp of a simple character and may be effectively used as a securing means for the rail in normal position and as a supporting means for the rail in inverted or ball down position, and by using a spike other clamping means usually adopted in rails of this character are dispensed with, thereby materially reducing the cost of manufacture of the improved tie. Moreover, the spike 16 as a clamp holding means may be easily applied and readily removed and will serve as a reliable means in performing either of its functions.
80

When it is desired to disorganize a track rail construction embodying the improved form of tie the several parts may be readily dissociated and moved from one place to another and quickly assembled in practical
85 100 relation.

What is claimed is:

1. In a mine railroad or track construction, a tie having the opposite extremities bent upwardly and downwardly and formed with a flat seat member secured to the body of the tie and having an inner terminal upwardly and outwardly directed stop bend, a chamber being formed by bending the extremity of the tie as specified, said chamber having an opening in its inner wall, a rail disposed in the seat member, and a spike inserted through the said opening in the inner wall of the chamber and removably engaging the outer portion of the flange of the rail.
105 110 115

2. In a mine railroad or track construction, a tie having each extremity thereof bent upwardly and inwardly and then downwardly to form a chamber and continuing into a flat seat member secured to the body of the tie, the inner wall of the chamber having an opening therethrough, a loose clamping device inserted through said inner wall of the chamber and adapted to engage the outer portion of a rail flange, a rail having its flange engaging said seat member and held by said clamping device, and a wedge driven through the said chamber and engaging the outer end of the clamping device.
120 125 130

3. In a mine railroad or track construction, a tie having each extremity thereof bent upwardly and inwardly and then downwardly to form a chamber and continuing 5 into a flat seat member which is secured to the body of the tie, the body of the tie forming the bottom of the chamber and having a slot therein and the inner wall of the chamber formed with an opening therethrough, a 10 rail mounted in the seat member and having the base flange thereof engaging the latter, a clamping spike inserted through the opening in the inner wall of the chamber and having a portion of the head thereof engaging said 15 slot, and a wedge block driven through the chamber and engaging the head of the spike to hold the latter in clamping position relatively to the outer portion of the flange of the rail.
- 20 4. In a mine railroad or track construction, a tie having each extremity thereof bent upwardly and inwardly and then downwardly to form a chamber and the outer wall of a seat which is provided with an 25 overhanging projection, the seat continuing

into a flat member which is secured to the body of the tie and terminating at its inner portion in an upwardly bent stop, the bent extremity of the tie forming a chamber whose inner wall is the downwardly bent 30 portion of said extremity, the latter wall having an opening therein, a rail having its base flange engaging the flat portion of the seat with the inner edge of the flange fitting against the stop, a rail having its ball inverted and inserted between the first named rail and the said projection, the flange of the inverted rail resting on the ball of the first named rail, and a clamping means inserted through the opening in the inner wall of the 35 chamber and engaging the flange of the first named rail, the head of the clamping device or means being held in the said chamber.

In testimony whereof I have hereunto set my hand in presence of two subscribing witnesses. 40

ERNEST HUTTON.
